CLAIM

The ornamental design for a bench riveter, as shown and described.

DESCRIPTION

FIG. 1 is a perspective view of a bench riveter in accordance with the present invention;

FIG. 2 is a left side view of the bench riveter shown in FIG. 1;

FIG. 3 is a right side view thereof;

FIG. 4 is a top view thereof;

FIG. 5 is a bottom view thereof;

FIG. 6 is a front view thereof; and,

FIG. 7 is a rear view thereof.

The bench riveter is designed to be placed on a workbench and the handle rotated to move a driver downwardly to install a rivet retained by an anvil into a workpiece.

The broken lines showing a driver and an anvil used therewith in the drawings depict unclaimed environmental subject matter and form no part of the claimed design.
